METHOD AND APPARATUS FOR YARN
PROCESSING

Frederick R. Millhiser, Chesterfield County, Va.,
assignor to E. I. du Pont de Nemours & Company, Wilmington, Del., a corporation of Delaware

Application January 9, 1942, Serial No. 426,184

10 Claims. (CL 28—71.5)

This invention relates to a method and apparatus for imparting an impelling, directional force to a yarn. More particularly, the invention relates to a method and apparatus for imparting a sufficient impelling, directional force to a yarn to positively forward the same which force will, however, be insufficient to impart an appreciable tension to the yarn.

In numerous methods for the production or processing of rayon yarn, it is essential that the yarn be forwarded in a uniformly controlled positive manner but without imparting any appreciable amount of tension to the yarn.

It is, therefore, an object of the present invention to provide an improved method and apparatus for positively impelling a yarn in a uniformly controlled manner without imparting substantial tension to the yarn and without disarranging the parallel filaments in a yarn.

Other objects of the invention will appear hereinafter.

In accordance with the present invention an impelling force is imparted to a yarn by positioning the yarn between the converging walls of a substantially V-shaped groove and directing an impelling stream of liquid against the yarn positioned between said converging walls. To prevent undesirable disarrangement of the filaments by flooding of the yarn, and to provide sufficient impelling force by the liquid, the above-said stream of liquid should have a mass per unit of time between three and fifteen times the mass of yarn passing through the groove within the same unit of time. The velocity of the stream should be greater than the impelled speed of the yarn, and preferably it should be at least two times the impelled speed of the yarn.

The details of the present invention will be more clearly apparent by reference to the following description when taken in connection with the accompanying illustration, in which:

Figure 1 is a perspective view of a device constructed in accordance with the present invention.

Figure 2 is a partial cross-sectional view through the apex of the V-shaped groove shown in Figure 1.

Figure 3 is a side elevational view, with parts shown in perspective, illustrating one application of apparatus constructed in accordance with the present invention.

Figure 4 is a perspective view of two yarn-impelling devices, constructed in accordance with the present invention, arranged to direct a yarn towards a belt collecting means.

Figure 5 is a top plan view of a modified form

of V-shaped groove for a yarn-impelling device constructed in accordance with this invention.

Referring to the drawing, reference numeral 11 designates, generally, a yarn-impelling device as hereinafter described in detail. The device 11 comprises a plate 13 provided with a V-shaped groove 15. A supporting bracket 17 is connected to plate 13. The supporting bracket 17 has a ledge 19 slightly overhanging the plate 13. A nozzle 21 is positioned in the ledge 19. The nozzle is provided with a fine tubular point 23 which is directed at an acute angle against the line of juncture of the converging walls of the V-shaped groove 15. This is clearly shown in Figure 2 of the drawing. It will be here noted that in accordance with the preferred construction, the fine tube 23 is positioned at an angle of about 20° to the vertical rear wall of the notch. A liquid supply conduit 25 is connected to the inlet side of the nozzle, and a pump 27 is connected to the conduit to pass a liquid under pressure therethrough. A yarn 29 is positioned between the converging walls of the V-shaped groove 15. The liquid passing from the fine tubular point 23 of the nozzle will then be directed against the yarn and toward the line of juncture of the converging walls of the V-shaped groove. As shown in Figure 2 of the drawing, the liquid will pass against the yarn in the apex, or bottom, of the groove substantially at the point 31 thereby causing the yarn to be impelled along the bottom of the groove in the direction of the arrow. The stream of liquid will also cause the yarn to be maintained in the bottom of the groove.

In accordance with the preferred construction of the present invention the grooved plate 13 and the tubular point 23 of the nozzle will be positioned at such an angle to each other that the stream of liquid issuing from the nozzle will impinge in a downward direction on the lower portion of the line of juncture of the converging walls of the V-shaped groove 15. The grooved plate 13 is preferably constructed of a corrosion-resistant alloy having a thickness of approximately $\frac{1}{16}$ inch. The groove 15 in the plate is preferably of such a shape that the converging walls of the groove form an angle of approximately 60° with each other, the walls of the groove being normal to the flat top and bottom surface 50 of the plate 13. The tubular point 23 of the nozzle preferably comprises a platinum tube of about $\frac{1}{16}$ inch in length and having an internal diameter of about 0.011 inch.

Referring to Figure 2 of the drawing, it will be noted that the plate 13 in which the groove 15 is

formed is made of gradually increasing thickness. This has been done to increase the angle between the yarn passing from the plate and the bottom of the plate. This angle should be at least 90°.

Figure 3 of the drawing illustrates a yarn-producing apparatus of the general type disclosed in British Patent No. 379,880. The yarn 29 is removed from the coagulating and/or regenerating bath by means of a feed wheel comprising feed roller 33 and cooperating yarn-separating roller 35. The yarn 29 is generally passed a plurality of times about said rollers to prevent slippage when a comparatively high tension is applied to the yarn in the spinning bath. The yarn 29 is then directed to a slowly moving belt designated by numeral 37. In accordance with the above-said British patent process, the yarn is to be collected by the belt 37 in a completely relaxed condition. If the yarn is merely dropped to the belt from the separating roller 35, there will be a tendency of the yarn to cling to roller 35 and possibly wind up on said roller. In order to feed the yarn from the rollers 33 and 35 to the collecting belt 37 without imparting substantial tension to the yarn, a plate member 13 containing a V-shaped groove 15 is positioned adjacent the belt 37. The yarn 29 is positioned in the bottom of the V-shaped groove and a nozzle 21 is positioned to direct a stream of liquid against the bottom of the groove in the direction of the movement of the thread. The yarn will thereby be prevented from clinging to roller 35 and will be caused to drop in a substantially free and completely relaxed condition on to the belt 37. It is preferred that the yarn passing into the bottom of the groove 15 have an angle of substantially 10° with the line defining the bottom of the groove. The slight angular tension thus imparted to the yarn aids in properly positioning the latter in the groove and aids in holding the same under the influence of the impinging stream of liquid. Although the angular path of the yarn from the roller 35 to the groove 15 somewhat retards the advance of the yarn through the guide, this is of relatively minor importance compared to the advantage accruing from the provision of the angular path of the yarn.

The grooved plate 13 is preferably positioned about 1 to 2 inches above the conveyor belt, although this distance may vary from $\frac{1}{2}$ to 6 inches. The belt may be mounted almost any desired distance below the feed wheel. It can, if desired, be mounted within one foot below the feed wheel; however, for purposes of practical design and to insure adequate head room, it is preferred that the belt be approximately 5 to 7 feet below the feed wheel.

Referring to Figure 4 of the drawing, reference numeral 41 designates a slowly moving belt which is provided with means, not shown, for moving the belt longitudinally at periodic intervals for short distances. Two yarn-impelling devices 11 are positioned a short distance above the belt to forward yarns from their respective feed rollers (not shown) to the belt in a completely relaxed condition. The yarns 29, as they drop on to the belt, form small self-imposed ringlets which overlap each other as the yarn-impelling devices are traversed transversely of the belt. For the purpose of obtaining a transverse movement of the yarn-impelling devices, they may be attached to a traverse bar 43 which is reciprocated by means of the cam 45. The movement

of the reciprocating traverse bar 43 is synchronized with the step-wise intermittent movement of the belt 41 so that the yarn will be laid on the belt in a solid mat comprising overlapping rows 5 of overlapping ringlets.

Referring to the modification shown in Figure 5 of the drawing, the plate 13 is provided with a V-shaped groove 15 having a slightly rounded apex or bottom 51. This form of device may be used when impelling a heavy denier yarn; that is, a yarn having a denier of 1100 or greater.

Because of the positioning of the tubular point 23 of the nozzle at an acute angle to the line of juncture of the walls of the V-shaped groove 15, the stream of liquid striking the yarn positioned within the bottom of the groove serves at once to direct the yarn through the groove and to maintain it positioned against the apex or bottom of the groove. Thus, this impinging stream of liquid subjects the yarn to an impelling force which is of very slight but inappreciable tension. The tension will, of course, be sufficient to prevent the wrapping of the yarn about the feed roller or separating roller as shown in Figure 3 of the drawing. The V-shaped groove supports the yarn and serves to hold the advancing yarn in position and keep it constantly under the influence of the downwardly directed force of the liquid. The magnitude of the downwardly directed force imposed on the yarn by the liquid stream is dependent on the total mass and the velocity of the stream, and upon the angle at which it strikes the yarn positioned in the bottom of the groove. It is preferred that the stream of liquid be very fine so that undue flooding of the yarn will be avoided. Preferably, the stream of liquid issuing from the nozzle per unit of time should have a mass from three to fifteen times the total mass of yarn passing through the guide within the same unit of time. If the ratio of liquid to yarn mass is less than three, the stream will not possess sufficient driving force to impel the yarn with a uniformly controlled force. If the ratio is greater than 15, the stream will flood the yarn and thereby cause the filaments of the yarn to be deranged and possibly damaged.

The process and apparatus of the present invention is preferably operated with the advancing yarn passing in a vertically downward direction; however, it can also be used in processes where the yarn is directed at substantially any angle to the vertical. In fact, apparatus constructed in accordance with the present invention is capable of directing an advancing yarn of 150-denier in a horizontal, or even upward, direction for a distance of several inches.

The dimensions and operation of the device of the present invention will, of course, depend somewhat upon the denier and spinning speed of the yarn. For example, as the denier is increased or the spinning speed is increased, it will be preferred to increase the impelling force of the impinging stream of liquid. This may be done by increasing the pressure on the liquid so as to increase both the mass and velocity of the stream. Alternatively, the inner diameter of the nozzle may be decreased and the pressure maintained constant or increased. In any event it is necessary that the stream possess a velocity that is always slightly greater than the yarn speed and preferably at least two times the yarn speed. Obviously, many possible combinations of nozzle diameter and liquid pressure can be employed to obtain any desired relationship to the denier and speed of the yarn. In general, satisfactory re-

sults can be obtained by using a nozzle having an inner diameter of the order of 0.011 inch and varying the pressure. However, the invention contemplates the use of nozzles having a diameter of from 0.005 to 0.02 inch which will impart the velocity and mass of liquid referred to above.

In general, the nozzle or the tubular point thereof should be mounted as close to the apex of the grooved plate 13 as is practical, preferably within $\frac{1}{2}$ inch. By thus positioning the nozzle close to the apex of the groove, the liquid will impinge on the yarn as a fine stream and the tensioning effect of the liquid on the yarn will actually serve to hold together, in a compact bundle, the filaments comprising the yarn. If the nozzle is spaced from the apex of the groove a materially greater distance than $\frac{1}{2}$ inch, the stream, because of its small mass, will separate into small individual droplets, and its velocity will be greatly decreased. Thus, its efficiency in directing the advancing yarn will be greatly diminished.

When used in connection with the spinning of viscose rayon yarn, desirable results will be obtained if the impelling liquid forced through the nozzle is of the same composition as the coagulating bath employed in the spinning process. Nevertheless, water or other liquids can also be used. If desired, filtering means can be inserted within the conduit supplying the nozzle with liquid, or such means may even be positioned within the nozzle.

The grooved plate 13 is preferably formed from a piece of metal having a thickness of approximately $\frac{1}{4}$ inch although thicknesses slightly less and up to $\frac{1}{2}$ inch can be used for this purpose. It is generally not desirable to increase the guide thickness above about $\frac{1}{2}$ inch because the resulting increased frictional contact of the V-shaped groove with the yarn requires the impinging stream to exert a much greater force against the groove. The materials of the device of the present invention may be made of substantially any non-corrosive metal, or of a suitable plastic material or ceramic material. A desirable composition of the grooved plate comprises a fused titanium oxide product sold under the trade name "Alsimag."

As above referred to the angle between the descending yarn passing from the bottom of plate 13 and the bottom of the plate should be at least 90° . This angle is designated in Figure 2 as angle x . If this angle is materially less than 90° , the descending yarn tends to cling to the lower surface of the groove rather than to be impelled downwardly in a straight line.

Although the invention has been described with particular reference to the spinning process disclosed in the above-mentioned British patent, it is not so limited. It can also be used with efficiency to direct yarn to other types of receiving means, for example, to a centrifugal bucket in a bucket spinning process. When used to direct yarn to a centrifugal bucket, the device of the present invention can satisfactorily be mounted above the reciprocating funnel guide of a bucket spinning apparatus, and the device will serve to guide the yarn into said funnel.

The method and apparatus of the present invention is not limited to use with freshly spun yarn. It is, in general, suitable for use in any case where it is desired to direct a yarn with a

minimum of tension and without causing flooding of the yarn. It is particularly valuable in those cases where the yarn-collecting means exerts no directive or pulling force on the yarn.

The present invention finds particular utility in connection with the spinning of yarns at high speeds, that is, speeds of the order of 8,000 to 10,000 inches per minute. Nevertheless, the invention can also be used to advantage with low spinning speeds of the order of 3,000 inches per minute.

By means of the present invention, a yarn can be impelled with a uniformly controlled force without imparting an appreciable tension to the yarn, and without causing a flooding of the yarn.

Since it is obvious that many changes and modifications can be made in the above-described details without departing from the nature and spirit of the invention, it is to be understood that the invention is not to be limited to the details described herein except as set forth in the appended claims.

I claim:

1. A yarn impelling device comprising a member having converging walls forming a substantially V-shaped groove, a nozzle spaced from said groove, said nozzle directed at an acute angle toward the line of juncture of said converging walls, said device being adapted to receive a yarn adjacent said line of juncture of said converging walls, and means for passing a yarn impelling stream through said nozzle against said yarn.

2. In a device as defined in claim 1 in which said line of juncture does not exceed $\frac{1}{8}$ inch in length.

3. In a device as defined in claim 1 in which said line of juncture forms an angle of at least 90° to the surface of said member from which the yarn emerges.

4. In a device as defined in claim 1 in which said nozzle has an internal diameter of about 0.005 to 0.02 inch.

5. The method of imparting a uniformly controlled impelling force to a yarn which comprises positioning the yarn against a surface, and directing a stream of liquid at an acute angle against said yarn and towards said surface as the sole means to move the yarn along said surface, said stream having a velocity exceeding the linear velocity of said yarn.

6. A method of imparting a uniformly controlled impelling force to a yarn which comprises positioning a yarn against a surface, and directing a stream of liquid at an acute angle against said yarn and toward said surface as the sole means to move the yarn along said surface, said stream having a velocity exceeding the linear velocity of said yarn, and having a mass per unit of time between 3 and 15 times the mass of yarn passing along said surface per unit of time.

7. The method as defined in claim 5 in which the acute angle is about 20° .

8. The method as defined in claim 5 in which said liquid is water.

9. The method as defined in claim 5 in which the liquid is a coagulating liquid for said yarn.

10. The method as defined in claim 5 in which the velocity of said liquid is at least two times the velocity of said yarn.

FREDERICK R. MILLHISER.
